UNITED STATES PATENT OFFICE

JULIUS BRENDLE, OF ZURICH, SWITZERLAND

TIME-RECORDING INSTRUMENT

Original application filed January 24, 1925, Serial No. 4,523, and in Switzerland June 16, 1924. Divided and this application filed January 12, 1928. Serial No. 246,367.

The present invention relates to improvements in time-recording instruments and is a division of my application Ser. No. 4,523, filed January 24, 1925.

5 In particular the invention has reference to the indicating device in a workman's time-recorder in which the type device driven by a driving train is provided with a divisor taking into account the non-working periods for 10 indicating the effective working time.

The subject matter of the present invention differs from that of the above mentioned application in that a wheel of the recording type device which is continuously rotated by 15 the driving train is provided with teeth interrupted in accordance with the non-working periods for the purpose of interrupting the stepping of a recording type member (which may be a type wheel or a type lever).

20 Constructional example of the subject matter of the present invention is illustrated on the accompanying drawings which show in elevation only those parts of the constructional example which are necessary for explaining the invention,

25 With further reference to the constructional example illustrated 1 denotes the type wheel rigidly mounted on the shaft 2 and provided with printing types 3, the figures on 30 which form a consecutive scale of units of the working time, for instance tenth of working hours and the numbering being 0.0, 0.1, 0.2, 0.3 . . . 1.0, 1.1 . . . up to 12.00 indicating 12 working hours.

5 A stepped movement is imparted to the type wheel 1 by means of a two-armed ratchet lever 4 turnably mounted on a pin 6 fixed to the plate 5. The ratchet lever 4 carries at its one end a pusher pawl 7 which is urged by 10 means of a spring 8 against pins 9 arranged in a circle on a disc 10 rigidly connected to the type wheel 1. The number of pins 9 corresponds to the number of printing types 3 arranged on the type wheel 1. The other arm 5 of the lever 4 is a pawl 11 cooperating with a ratchet disc 12 and urged against the latter by the spring 13. The disc 12 is rigidly mounted on a shaft 14 which is continuously driven by a clock-work not illustrated in the direction of the arrow shown in Fig. 1 and

the circumference of the disc 12 is provided with toothed portions 15 corresponding to the working time and blank portions 16 which correspond to the non-working intervals.

During the working time the teeth of one 55 or the other of the toothed portions 15 of the disc 12 cooperate with the pawl 11 and every tooth causes a rocking movement of the lever 4 against the influence of the spring 13. Thereby the pusher pawl 7 cooperating with 60 the pins 9 causes a turning movement of the type wheel 1 through a determined angular extent whereupon the pusher pawl 7 is in a position to cooperate for instance with the next pin 9 and so on.

65 The angular stop movement of the type wheel imparted by each action of the ratchet lever shall occur after every 6 minutes. If I designates the beginning of the working time, for instance 7 o'clock a. m., the blank portion 70 I^a—I^b on the ratchet disc 12 will have reached the pawl 11 of the ratchet lever 4 at 8.48 a. m. after eighteen ratchet movements of the lever 4 and thereby after eighteen step by step movements of the type wheel 1, the 75 blank portion I^a—I^b corresponds to the breakfast interval. The ratchet lever 4 is now not operated by the ratchet disc 12 and the type wheel is not turned until the first tooth of 80 the toothed portion beginning at I^b has reached the pawl 11 during the further turning motion of the disc 12 under the actuation of the clock work. With the peripheral extent of I^a—I^b shown in Fig. 1 this will happen at 85 9 a. m. when the intermittent turning movement of the type wheel 1 starts again.

The ratchet lever 4 is again inoperative at 12 o'clock when the beginning of the blank portion II—III of the circumference of the disc 12, which corresponds to the midday interval, has reached the pawl 11. At 1.30 p. m., i. e. when the toothed portion starting at III acts upon the pawl 11 the intermittent turning of the type wheel is again effected until 5 o'clock p. m., when the blank portion between IV 90 and I comes to cooperate with the pawl 11.

95 The peripheral extent of a blank portion IV—I corresponds to two hours and this portion may be used for actuating the ratchet lever 4 by screwing a toothed segment to the 100

disc 12, whereby the type wheel indicates these time units as over-time. In consequence of the blank portions in the ratchet disc the type wheel is only turned during the effective working time and it indicates the latter.

5 The toothed portions on the ratchet disc 12 which take into account the intervals in the working time by their peripheral distance from each other may also be detachably secured to a ratchet disc in a similar manner as has been disclosed in my above mentioned application, so that the segments might be exchanged for others the toothing of which corresponds to different units of time or shows 10 a different peripheral extent to take into account non-working periods of a different duration.

15 I claim:

1. In a workman's time recorder, a type 20 wheel having a series of concentric time divisions, a uniformly rotated wheel having a series of teeth corresponding to said time divisions but interrupted in accordance with non-working periods, and an operative connection between said type wheel and said other wheel for imparting rotation to the 25 former, said type wheel directly indicating the working time.

2. In a workman's time recorder, a type 30 wheel having a series of concentric time divisions, a ratchet wheel having a series of teeth corresponding to said time divisions but interrupted in accordance with non-working periods, and means to control the rotation 35 of said type wheel from said ratchet wheel, said type wheel directly indicating the working time.

In testimony whereof, I have signed my name to this specification.

40 JULIUS BRENDLE.
